UNITED STATES PATENT OFFICE.

JOHN C. THOMPSON, OF CINCINNATI, OHIO.

WRINGER-SUPPORT.

1,222,161.

Specification of Letters Patent. Patented Apr. 10, 1917.

Application filed December 12, 1912. Serial No. 736,412.

To all whom it may concern:

Be it known that I, JOHN C. THOMPSON, a citizen of the United States, residing at Cincinnati, in the county of Hamilton and State of Ohio, have invented a certain new and useful Wringer-Support, of which the following is a specification.

The object of my invention is to provide a gearing device of simple, durable and inexpensive construction whereby one wringer may be mounted in operative position on a washing machine tub in any ordinary manner, and whereby another wringer may be mounted in position to be operated through the first wringer.

A further purpose of my invention is to provide in such a device, means for mounting a wringer on a washing machine in such a manner that it may be turned on one end to swing from one position to another while being at all times in gear with operating mechanism.

A further object is to provide in such a device means for mounting a swinging wringer in such a manner that the wringer may be readily and easily detached from a tub body without the removing of nails, screws or other fastening device.

A further object of my invention is to provide a tub mounted upon a suitable standard and provided with mechanism whereby the tub may be raised or lowered as desired.

A further object is to provide a movable, detachable platform.

My invention consists in certain details, in the construction, arrangement and combination of the various parts of the device whereby the objects contemplated are attained, as hereinafter set forth, pointed out in my claims and illustrated in the accompanying drawings in which—

Figure 1 shows a side elevation of a washing machine tub equipped with a gearing device embodying my invention.

Fig. 2 shows a top or plan view of the same.

Fig. 3 shows a top or plan view partly in section of part of my improved gearing device, two wringers, and a portion of a tub.

Fig. 4 shows a vertical sectional view through my improved gearing device and gear casing.

In the accompanying drawings I have used the reference numeral 10 to indicate an ordinary washing machine tub.

Instead of being mounted on legs I have provided the following means for supporting my machine:

I provide a standard or base 11 having a central vertical bearing 12 provided with a vertical screw threaded opening. Extending downwardly from the center of the bottom of the tub is a heavy screw threaded rod 13 received in the opening in the bearing 12. It will be seen that by rotating the tub 10 the rod 13 will be screwed up or down in the bearing 12 and the tub 10 will be raised or lowered to suit the desire of the user. The machine may be operated from any suitable source of power such as for instance, an electric motor 14. Ordinary gearing mechanism is employed for transmitting motion to the dolly shaft.

Mounted on the lower portion of the tub body, and spaced therefrom, is a circular track 2. I provide a pair of frame members 3, each of which is provided with a hook member 4 at its inner end slidably mounted on the track 2. The frame members 3 form part of a movable, detachable platform, and when the latter is in position for use, said members extend outwardly and toward each other from the tub body, as shown in Fig. 1.

Telescopically mounted, with relation to the members 3, are frame members 5 which converge at their outer ends. The inner ends of the frame members 3 are connected by a cross member 6. Pivoted to the outer ends of the members 5 is a supporting leg 7 in the lower end of which is mounted the wheel 8. A brace 9 is pivoted to the middle of the cross member 6 and to the supporting leg 7.

When in use, the parts just described, are in position shown in Figs. 1 and 2. The platform may be detached by lifting the members 3 out of engagement with the track 2. The members 5 are adjustably secured to the members 3 respectively, by means of set

screws 9^a. The movable platform may be raised and allowed to rest against the tub body and by loosening the set screws 9^a, the respective members 5 and 3 may be 5 telescoped, as shown by the dotted lines in Fig. 1.

Mounted on the tub 10 is an ordinary wringer 15 having the upper roll 15^a and the lower roll 15^b which is operated from the 10 source of power 14 by suitable mechanism. The shaft 16 of the lower wringer roll of the wringer 15 extends beyond the frame of the wringer on the end opposite the end of the wringer which is connected with the operating mechanism, as clearly shown in Fig. 4. On the outer end of the shaft 16 is a beveled gear 17. Mounted upon the tub 10, by means of a flange 18 and secured to the frame member 19 of the wringer 15, by 20 means of flanges 20 and 21 is a bracket and gear casing member 22 on which is formed a bearing 23 received within a suitable opening in the frame member 19 and forming a bearing for the shaft 16.

25 The main body of the gear casing member 22 extends away from the frame member 19 in a substantially horizontal plane. Rotatably mounted in the gear casing member 22 is a vertical shaft 24 on the upper end of 30 which is a horizontal beveled gear 25 in mesh with the beveled gear 17. The gear casing 22 is provided with a cover member 26, which is secured to the gear casing member 22 by means of bolts or screws 27. In 35 the solid lower body portion of the gear casing member 22 is a horizontal slot 22^a received in which is an arm 28 formed on a wringer supporting bracket 29 which extends away from the casing member 22 in a 40 substantially horizontal plane. Formed in the upper surface of the wringer supporting bracket 29 are sockets 30 in which are removably received and supported the lower ends of the vertical end members 31 and 32 of a 45 second wringer 33 having rolls 15^a and 15^b.

The wringer 33 is mounted to swing in a horizontal plane and is arranged to be readily detached from the tub when the operator so desires. Formed in the side walls 50 of the gearing cover 26 and of the member 22 is a horizontal slot 34. The shaft 35 of the lower wringer roll of the wringer 33 extends through the slot 34 into the space between the gear casing member 22 and the cover member 55 26 and is adapted to swing horizontally in the slot 34. On the end of the shaft 35 is a beveled gear 36 in mesh with the beveled gear 25. The arm 28 is provided with an opening which forms a bearing for the shaft 24 where- 60 by the arm 28 is pivotally mounted to swing in a vertical plane. It will therefore be seen that the wringer 33 may be swung on a circle with the arm 28 traveling in the slot 22^a, and the shaft 35 traveling in the slot 34 having

its center at the center of the shaft 24 and 65 that the beveled gear 36 will at all times be in mesh with the beveled gear 25.

At one end of the slot 34 is an opening 40^a 70 in the gear case covering 26 of suitable form and size to permit the shaft 35 and the beveled gear 36 to be lifted in a vertical line whereby the wringer 33 may be entirely removed from the bracket and gear casing member 22. Formed on the lower outer portion of the gear case member 22 is a downwardly extending curved flange 37 in which are formed a plurality of holes 38 arranged on a horizontal line. Slidably mounted below the wringer supporting member 29 is a slide bolt 39 having on its outer end a handle 40 and having its inner end arranged to enter the holes 38 in different positions of the movement of the wringer 33. I provide a spring 41 for normally holding the slide rod 39 at the inward position of its movement. It will be seen that the wringer 33 may be fixed in various positions of its movement by causing the slide rod 39 to enter the various holes 38.

90 In the practical operation of my improved gearing device assuming that the wringer 33 is installed in position and that it is desired to use the same, it may be adjusted at various angles with relation to the tub body and to the wringer 15 by withdrawing the slide rod 39 from the opening 38 in which it is received and by swinging the wringer 33 around the gear case member 22, the pivotal point of the means by which the wringer is mounted being the center of the shaft 24. 95 If it is desired to entirely remove the wringer 33 the slide rod 39 is held in its inoperative position and the wringer 33 is swung to position with the beveled gear 36 below the opening 40^a in the gear case cover 100 26. The wringer is then lifted upwardly around the gear case member 22, the pivotal point of the means by which the wringer is 105 mounted being the center of the shaft 24. If it is desired to entirely remove the wringer 33 the slide rod 39 is held in its inoperative position and the wringer 33 is swung to position with the beveled gear 36 below the opening 40^a in the gear case cover 110 26. The wringer is then lifted upwardly around the gear case member 22, the pivotal point of the means by which the wringer is 115 mounted being the center of the shaft 24. The wringer 33 is then lifted upwardly out of the sockets 30 and the gear 36 is lifted out of the cover 26 when the wringer 33 may be disposed of as may be desired.

When the wringer 33 is in its operative 110 position installed on the machine, it is operated through the wringer 15 and the gears 17, 25 and 36.

115 It will be seen that my improved gearing device has the advantage of furnishing means whereby a wringer may be quickly and easily installed in position with relation to a washing machine tub and whereby the wringer may be swung to various angles with relation to the tub and by which said wringer may be held in any position desired. The wringer is at all times in mesh with the stationary wringer and may be operated by the same means which operates said stationary wringer. The second wringer may be 120 readily removed from the machine by swinging it to the proper position and lifting it upwardly. It is quickly and easily installed.

in its operative position without use of tools, and without necessity for screws, nails or other removable parts.

I claim as my invention:

having formed thereon a horizontal arm received in said horizontal slot in said gear casing and having an opening formed therein in which said vertical shaft is rotatably mounted, said casing and said supporting member being so formed as to permit said supporting member to swing in a horizontal plane on said vertical shaft as a pivot, and

means for securing said supporting member in various positions of its swinging movement. 10

Des Moines, Iowa, September 27, 1912.
JOHN C. THOMPSON.
